UNITED STATES PATENT OFFICE.

SOLOMON WILE, OF ROCHESTER, NEW YORK.

SLICING MACHINE.

Application filed June 24, 1922. Serial No. 570,643.

To all whom it may concern:

Be it known that I, SOLOMON WILE, a citizen of the United States, and resident of Rochester, in the county of Monroe and 5 State of New York, have invented certain new and useful Improvements in Slicing Machines, of which the following is a specification.

The present invention relates to slicing 10 machines, and an object thereof is to provide a slicing machine, which will be durable in construction, simple in operation and inexpensive to manufacture. Another object of the invention is to provide an improved mechanism for operating the longitudinally movable carriage, so that a maximum movement of said carriage may be obtained. Still another object of the invention is to provide an improved operating 15 mechanism for the rotary cutter or knife. A further object of the invention is to improve the feeding mechanism for the transversely movable carriage. Another and still further object of the invention is to provide a 20 feeding mechanism for a transversely movable carriage, having provision whereby the carriage may be accurately fed, step by step, any desired amount, even to a very small fraction of an inch. A still further object 25 of the invention is to provide a construction in which the transversely movable carriage is held against feeding toward the knife under the action of the knife during the cutting of the material on the carriage. Another 30 and still further object of the invention is to provide a feeding mechanism for the transversely movable carriage, embodying a ratchet wheel and pawl with means for controlling the pawl, so as to vary the 35 engagement between the pawl and the ratchet wheel, to change the amount of feeding of the feeding mechanism. Another and still further object of the invention is to provide a feeding mechanism for a longitudinally 40 and transversely movable carriage, embodying a ratchet wheel and pawl with a detent operated upon the longitudinal movement of the carriage and adapted to hold the ratchet against turning under the 45 action of the cutting blade.

To these and other ends, the invention consists of certain parts and combinations of parts, all of which will be hereinafter described: the novel features being pointed 50 out in the appended claims.

In the drawings:

Fig. 1 is a plan view of the machine constructed in accordance with this invention;

Fig. 2 is a rear view of the machine illustrated in Fig. 1;

Fig. 3 is an enlarged plan view with the clamping means and knife guard removed, parts being illustrated in section;

Fig. 4 is a section on the line 4—4, Fig. 3;

Fig. 5 is a section on the line 5—5, Fig. 3;

Fig. 6 is a fragmentary plan view showing parts of the two carriages broken away for the purpose of illustrating the feeding mechanism for the transversely movable carriage;

Fig. 7 is a section on the line 7—7, Fig. 6;

Fig. 8 is an enlarged fragmentary view of the feeding mechanism for the transversely movable carriage;

Fig. 9 is a detail view of the means by which the locking detent of the ratchet wheel is operated;

Fig. 10 is another view of the operating abutments for the locking detent of the ratchet wheel;

Fig. 11 is a front view of the machine constructed in accordance with this invention;

Fig. 12 is a vertical section, showing the driving means for the cutter; and

Fig. 13 is a section on the line 13—13, Fig. 6.

In the illustrated embodiment of the invention, there is provided a main frame having a base portion 1 from which rises a hollow standard 2, supporting a top portion 3, which closes the upper end of the standard, the lower end of the standard opening through the base portion 1, so that the interior of the standard may be reached through the bottom of the main frame. The top portion extends from opposite sides of the hollow standard 2 and is provided with parallel guides 4 projecting from opposite sides thereof and having guide grooves 5 provided on these inner sides. On the guides 4, a longitudinally movable carriage 6 is mounted to slide, said carriage having depending and outwardly extending guides 7 operating in the grooves 5 of the guides 4.

Within the hollow standard 2 a cross piece 9 is arranged on which a shaft 10 is secured, there being arranged above said cross piece 9 to turn on said shaft, a gear member 11 provided on the under side with

a bevelled gear surface 12. With this bevelled gear surface a bevelled pinion 13 meshes, said pinion being secured to a shaft 14 which is journalled in a bearing 15 in the side of the standard 2. A fly wheel 16 is secured to this shaft 14 and has a crank handle 17 thereon through which the shaft 14 may be turned to turn the gear 11.

The gear 11 carries on its upper surface, 10 a projection 18 to which a pitman 19 is pivotally connected at 20, this pitman 19 preferably having a connection with the carriage 6 which will move the carriage on the main frame a greater amount than the 15 throw of the pitman. This result is secured, in this instance, by securing a rack 21 to the under side of the carriage 6 (see Fig. 4), said rack extending parallel with the line of movement of the main frame between the guides 4 and parallel with a rack 22 secured to the main frame. The pitman 19 has a gear 23 journalled on the outer end thereof at 24 and meshing with both of the racks 21 and 22. In order to maintain this 25 intermeshing relation, two plates 25 are secured on opposite sides of the gear 23 and lie above and below the racks 21 and 22, these plates projecting beyond the perimeter of the gear 23, so that the racks 21 and 22 30 operate between the plates in a groove or way provided by the outer portions of said plates. As the rack 22 is stationary, it is apparent that when the pitman 19 is moved, the gear 23 meshing with said rack 22 will 35 produce an increased movement in the rack 21, thus giving to the carriage 6 a greater movement than the throw of the pitman.

Arranged to operate in a plane at a slight 40 angle to the line of movement of the carriage 6 is a cutter 26 in the form of a circular bevelled disk which is secured to a shaft 27 journalled in a bearing 28 in the main frame and extending through the main frame into the hollow standard. A nut 45 29 secures this blade to the shaft against the collar 30 on the rear face of the blade, a groove collar 31 being interposed between the nut and the blade having a purpose which will be hereinafter set forth. On 50 the inner end of the shaft 27 a pinion 32 is arranged, which meshes with a gear 33 on a counter shaft 34, said counter shaft being journalled in the main frame and having a bevelled pinion 35 thereon which 55 meshes with the teeth 12 of the bevelled gear 11, thus providing a speed increasing means between the bevelled gear and the cutter.

In order to provide for guarding the edge 60 of the cutter, a segmental guard 36 is provided which is pivoted on a shaft 37 on the base portion 1 of the main frame to swing downwardly about a horizontal axis located below the axis of turning of the cutter. This segmental guard covers all of the

knife edge except the portion operating adjacent to the carriage, so that the exposed portion may cooperate with the material to be sliced. This exposed portion may be covered when not in use by a guard 38, 70 which is pivoted at 39 to one end of the segmental guard 36 and has a free end 40 adapted to enter into a notch 41 in the opposite end of the segmental guard 36. This movable guard 38 may also act as a stripper 75 and to this end it is movable to the position shown in full lines in Fig. 11 so that a portion thereof may enter the grooved washer 31, so as to support the guard and stripper in the position shown in Fig. 11. In order 80 that the guard 36 may be held in guarding position, a detent 42 is provided which is pivoted at 43 to the top 3 of the frame and has one arm provided with a laterally extending portion 44 for cooperating with the under side of the top 3 and the other arm adapted to cooperate with the guard 36 adjacent the pivot 39. The movement of the end 44 downwardly shifts the opposite end of this detent or latch 42 upwardly, 85 so that the guard 36 with the combined guard and stripper 38 may be swung away from the blade to permit the cleaning of the latter.

There may be also provided a receptacle 90 for receiving the sliced material. This receptacle, in this instance, is in the form of a shelf 45 with an upwardly extending rear portion 46 having a rearwardly extending projection 47 of dove-tail cross section 100 adapted to be received in a dove-tail notch 48 in the segmental guard 36 adjacent the pivotal connection between said guard and the combined guard and stripper 38.

Arranged to operate on the longitudinally 105 movable carriage 6 is a transversely movable carriage 49, which has its opposite edges movable beneath overhanging guides 50 formed on the top surface of the carriage 6, the top surface of the carriage 6 having at 110 one side of the carriage 49 an abutment 6^a against which the material may rest during the cutting action. The carriage 49 may be moved by a suitable mechanism which, in this instance, comprises a rack 51, secured to the under side of the carriage 49 between said carriage and the carriage 6. With this rack a pinion 52 meshes, this pinion being journalled on the carriage 6 at 53 and in turn meshing with the pinion 54 which is 120 journalled on a stub shaft 55 secured to a bracket 56 on the under side of the carriage 6 and extending through an opening 57 in the top of the carriage, the pinion 55 projecting through this opening above the top of the carriage to mesh with the gear 52. Secured to the shaft of the pinion 54 to turn with said pinion is a ratchet wheel 58, lying below the table 6. With this ratchet wheel, an advancing pawl 59 is adapted to engage, 130

this pawl being pivoted at 60 on a swinging arm 61 and being held toward the ratchet wheel by a spring 62. The swinging member 61 is journalled on the shaft of the pinion 54 to turn about an axis common to the axis of turning of the pinion of the ratchet wheel 58, this swinging movement of the member 61 being communicated to the pawl 59, and, when said pawl engages the ratchet wheel, 10 effects the movement of the ratchet wheel and consequently the movement of the pinion 54. Normally this swinging member is held in one position by a helical spring 63, which is secured at one end to the swinging member 61 and at the other end to the carriage 6 at 64. Movement of the swinging member 61 in the opposite direction is effected by a stop or abutment 65, secured to the top portion 3 of the main frame in such a position 20 that the member 61 is swung to advance the carriage 49 toward the knife blade, as the carriage 6 reaches that end of its movement and immediately prior to the advance of the carriage 6 toward the knife on the new cutting action, so that the material on the carriage 49 will be advanced for the new cutting action. With the end in view of preventing the retrograde movement of the ratchet wheel 58, there may be provided a 25 detent or pawl 66 pivoted at 67 to the bracket 56 and held toward the ratchet wheel 58 by a spring 68.

It has been found that it is desirable to provide a means for preventing the advance 30 movement of the ratchet wheel 58 under the pull of the knife on the material during the cutting action and to accomplish this, there may be provided a means in the form of an advance preventing detent 69 pivoted at 35 to the under side of the carriage 6 and having a nose 71, so disposed that it will engage the inclined faces of the ratchet wheel teeth to prevent the advance of the ratchet wheel. Of course, this detent 69 should not engage 40 the ratchet wheel 58 during the feeding or advancing movement of the ratchet wheel, and in order to throw the detent 69 out of engagement with the ratchet wheel during the feeding movement, the detent may have 45 a depending projection 72 which is adapted to cooperate with an abutment 73, pivoted at 74, to a block 75 which is secured to the top portion 3 of the main frame, a spring 73^a normally holding said abutment in operative position and permitting the yielding of such abutment on the return of the detent. Just prior to the engagement of the swinging frame 61 with the abutment 65, the detent 69 through its projection 72 cooperates with 50 the movable abutment 73 and is shifted away from detaining position. A spring 76 anchored at 77 to the carriage 6 and at 72 to the detent holds the detent in two positions, 55 this being due to the mounting of this spring which swings, so that its axis, in one posi-

tion, lies on one side of the axis of turning 70 on the detent 69 and, in the other position, lies on the opposite side of the axis of turning of said detent 69. The movement of the detent 69 to detaining position is effected 70 on the movement of the carriage 6 towards the knife on the cutting action. This result is secured, in this instance, by an abutment 78, pivoted at 79, to the block 75 and adapted to engage the depending projection 72 on 75 the detent 69 on the movement of the detent with the carriage 6 toward the knife blade on the cutting action, the spring 76, before mentioned, holding the detent in detaining position. A spring 78^a cooperates with the 80 abutment 78 to permit the latter to yield on the movement of the detent in the reverse direction over said abutment.

There may be provided means for varying the size of the cut, this being effected by 85 varying the amount of feed of the carriage 49 on the carriage 6. This result is accomplished, in this instance, by a thumb wheel 80 mounted on a shaft 81 and having graduations 82 for cooperation with a fixed 90 index 83. A spring arm 80^a with a tooth 80^b thereon cooperates with a notched portion 80^c on the thumb wheel to hold the latter in its adjusted position. The shaft 81 of the thumb wheel has an arm 84 extending laterally therefrom and pivotally connected to a link 85. This link in turn is pivotally connected at 86 to a controlling member 87 for the pawl 59. The controlling member is, in this instance, in the form of a disk 100 journalled on the hub of the pinion 54 and having its periphery formed on two curves 88 and 89 concentric to the axis of turning of the disk 87, but having radii of different length. The curve 88, with the longer radius, is arranged to cooperate with the pawl 59 and to hold the latter out of engagement with the ratchet wheel 58, while the curve 89, with the shorter radius, permits the pawl to enter into engagement with 105 the ratchet wheel 58. While the swinging member 61 is in normal position, where it is held by the spring 63, it lies in engagement with the curved portion 88 of the periphery of the controlling member 87, but, toward the end of the movement of the swinging member 61 under the action of the abutment 65, the pawl passes onto the curved portion 89 of the periphery of the controlling member 87 and shifts the ratchet wheel 58 an amount determined by the adjustment 110 of the controlling member 87. It is apparent that this amount may be varied by shifting the junction point between the curved portions 88 and 89 with reference to the ratchet wheel through the turning of the thumb wheel 80.

With the end in view of permitting the carriage 49 to be moved away from the knife, means is provided for throwing the detents 115 120 125 130

59, 66 and 69 out of cooperation with the ratchet wheel 58. This means is, in this instance, in the form of a lever 90 pivoted at 91 to the under side of the carriage 6 and 5 having a head 92 with a curved face 93 arranged to cooperate with lateral projections 94, 95 and 96, provided, respectively, on the portions or detents 59, 66 and 69.

10 Any suitable means may be employed for 10 clamping the material to be cut on the transversely movable carriage. In this instance, there is shown a clamping means, which forms the basis of another application filed by me, where will be found a full description 15 of the operation of the parts herein shown. Generally this clamping means embodies two posts 97 having slides 98 movable thereon and connected by a clamping bar 99.

20 The operation of the invention will be 20 understood from the foregoing description, but it may be summarized as follows: The material to be sliced is held by the clamping means on the transversely movable carriage or table 49 which is slidable on the longitudinally movable carriage 6. The latter is operated back and forth past the effecting cutting portion of the knife 26 by the turning of the crank handle 17 which turns the gear 12, the latter being geared to the cutting 25 knife or disk 26 through a speed increasing means and said gear 12 also being connected to the carriage 6 through a movement amplifying means which produces a larger movement in the longitudinally movable carriage, than is possible to obtain through the throw of the pitman, which is connected to said gear 12. When the carriage 6 approaches the end of its movement just prior to its movement to present the material to its cutting blade, the pawl or detent 69 is 30 shifted to free the ratchet wheel 58 and thereafter the pawl 59 is shifted to turn the ratchet wheel an amount determined by the setting member 80. This carries the carriage or table 49 toward the knife or cutting blade on the carriage 6, and, upon the movement of the carriage 6 toward the cutting blade, the detent 65 again interlocks with the ratchet wheel 58 and prevents the advance movement of the ratchet wheel under 35 the action of the knife in cutting the material.

40 From the foregoing it will be seen that there has been provided an improved slicing machine which is durable in construction and inexpensive to manufacture. An amplifying movement of novel construction is employed between the driving gear and the longitudinally movable carriage. An improved driving means is employed between the cutting blade and the drive or power shaft of the machine. There has also been 45 employed a novel means for controlling to a very fine extent the amount of feeding of the transversely movable carriage on the

longitudinally movable carriage. Provision has been made by which the action of the cutting blade on the material in cutting does not advance the transversely movable carriage on the longitudinally movable carriage. 70

What I claim as my invention and desire to secure by Letters Patent is:

1. In a slicing machine, the combination with a main frame, embodying a hollow standard, and a top substantially closing 75 said standard and projecting from opposite sides thereof, said top having guides thereon, of a carriage movable on said guides, a material supporting carriage movable on the first mentioned carriage 80 transversely of the line of movement of said first mentioned carriage, a rotary cutter on the base frame to operate upon the material on the material supporting carriage, a horizontally arranged gear mounted in 85 said hollow base frame and geared to the rotary cutter, driving connection between said gear and the first mentioned carriage, and a drive shaft journaled in the hollow base frame and geared to said horizontally 90 arranged gear.

2. A slicing machine comprising a base frame, cutting mechanism mounted on the base frame, a carriage movable past said cutting mechanism, a mechanism for moving said carriage embodying a rotary member, a pitman eccentrically connected with said rotary member and having a gear journaled on the outer end thereof, a rack on the base frame and meshing with said 100 gear, and a rack on the carriage meshing with said gear.

3. A slicing machine comprising a base frame, cutting mechanism mounted on the base frame, a carriage movable past said 105 cutting mechanism, a mechanism for moving said carriage embodying a rotary member, a pitman eccentrically connected with said rotary member and having a gear journaled on the outer end thereof, a rack 110 on the base frame and meshing with said gear, a rack on the carriage meshing with said gear, and two disks supported on opposite sides of said gear and cooperating with opposite sides of the two racks. 115

4. A slicing machine comprising a base frame, cutting mechanism mounted on the base frame, a carriage movable past the cutting mechanism, a material supporting carriage movable on the first mentioned 120 carriage transversely of the latter toward and from the cutting mechanism, and mechanism for feeding the second mentioned carriage on the first mentioned carriage embodying a toothed member mounted on the 125 first mentioned carriage and geared to the second mentioned carriage, a movable member mounted on the first mentioned carriage and carrying an advancing pawl cooperating with said toothed member, means on 130

9. A slicing machine comprising a base frame, cutting mechanism mounted on the base frame, a carriage movable past the cutting mechanism, a material supporting carriage movable on the first mentioned carriage transversely of the latter toward and from the cutting mechanism, and mechanism for feeding the second mentioned carriage on the first mentioned carriage embodying a toothed member mounted on the first mentioned carriage and geared to the second mentioned carriage, a movable member carrying an advancing pawl mounted on the first mentioned carriage and cooperating with said toothed member, means on the base frame cooperating with said movable member to effect the movement of the latter and through such movement to effect the movement of the toothed member, a pivotally mounted advance preventing detent for cooperating with said toothed member to prevent the advance movement of the latter independently of said advancing pawl, a spring connected to said detent at one side of the pivot of the latter and adapted to hold the detent in cooperation with the toothed member and also out of cooperation with said toothed member, and devices for shifting said detent into and out of cooperation with said toothed member.

10. A slicing machine comprising a base frame, cutting mechanism mounted on the base frame, a carriage movable past the cutting mechanism, a material supporting carriage movable on the first mentioned carriage transversely of the latter toward and from the cutting mechanism, and mechanism for feeding the second mentioned carriage on the first mentioned carriage embodying a toothed member mounted on the first mentioned carriage and geared to the second mentioned carriage, a movable member carrying an advancing pawl mounted on the first mentioned carriage and cooperating with said toothed member, means on the base frame cooperating with said movable member to effect the movement of the latter and through such movement to effect the movement of the toothed member, a pawl for preventing the retrograde movement of the toothed member, an advance preventing detent cooperating with the toothed member, and means for throwing out the advancing pawl, the pawl which prevents the retrograde movement and the advance preventing detent from cooperation with the toothed member.

11. A slicing machine comprising a base

frame, cutting mechanism mounted on the base frame, a carriage movable past the cutting mechanism, a material supporting carriage movable on the first mentioned carriage transversely of the latter toward and from the cutting mechanism, and mechanism for feeding the second mentioned carriage on the first mentioned carriage embodying a toothed member mounted on the first mentioned carriage and geared to the second mentioned carriage, a movable member carrying an advancing pawl, mounted on the first mentioned carriage and cooperating with said toothed member, means on the base frame cooperating with said movable member to effect the movement of the latter and through such movement to effect the movement of the toothed member, an advance preventing detent, and means for simultaneously throwing out the advancing pawl and the advance preventing detent from cooperating with the toothed member to permit the advance movement of the toothed member.

12. A slicing machine comprising a base frame, cutting mechanism mounted on the base frame, a carriage movable past the cutting mechanism, a material supporting carriage movable on the first mentioned carriage transversely of the latter toward and from the cutting mechanism, and mechanism for feeding the second mentioned carriage on the first mentioned carriage embodying a toothed member mounted on the first mentioned carriage and geared to the second mentioned carriage, a movable member carrying an advancing pawl, mounted on the first mentioned carriage and cooperating with said toothed member, means on the base frame cooperating with said movable member to effect the movement of the latter and through such movement to effect the movement of the toothed member, a pawl for preventing the retrograde movement of the toothed member, an advance preventing detent cooperating with the toothed member, and means for throwing out the advancing pawl, the pawl which prevents the retrograde movement and the advance preventing detent from cooperation with the toothed member.

13. A slicing machine comprising a base frame, cutting means on the base frame, a carriage movable on the base frame, a second carriage movable on the first mentioned carriage toward and from the cutting means, and means for advancing the second mentioned carriage on the first mentioned carriage comprising a toothed member movably mounted on the first mentioned carriage and geared to the second mentioned carriage, an advancing pawl movably mounted on the first mentioned carriage and cooperating with said toothed member, means on the base frame for shifting said pawl, and

means mounted on the first mentioned carriage to cooperate with said pawl to vary the amount of movement of the toothed member by said pawl.

14. A slicing machine comprising a base frame, cutting means on the base frame, a carriage movable on the base frame, a second carriage movable on the first mentioned carriage movable toward and from the cutting means, and means for advancing the second mentioned carriage on the first mentioned carriage comprising a toothed member movably mounted on the first mentioned carriage and geared to the second mentioned carriage, an advancing pawl movably mounted on the first mentioned carriage and cooperating with said toothed member, means on the base frame for shifting said pawl, and a member on the first mentioned carriage for cooperating with said pawl and adjustable to hold said pawl out of engagement with the toothed member during any desired portion of the movement of said pawl under the means on the base frame so that the amount of movement of the toothed member may be varied.

15. A slicing machine comprising a base frame, cutting means on the base frame, a carriage movable on the base frame, a second carriage movable on the first mentioned carriage toward and from the cutting means, and means for advancing the second mentioned carriage on the first mentioned carriage toward said cutting means, comprising a ratchet wheel mounted on the first mentioned carriage and geared to the second mentioned carriage, a swinging member

mounted to turn about the axis of the ratchet wheel, a pawl on said swinging member, means on the base frame engaging said swinging member to shift the pawl, and a member mounted to turn about the axis of turning of the ratchet wheel and cooperating with said pawl to hold the latter out of engagement with the ratchet wheel during any desired amount of movement of the swinging member.

16. A slicing machine comprising a base frame, cutting means on the base frame, a carriage movable on the base frame, a second carriage movable on the first mentioned carriage toward and from the cutting means, and means for advancing the second mentioned carriage on the first mentioned carriage toward said cutting means comprising a ratchet wheel, mounted on the first mentioned carriage and geared to the second mentioned carriage, a swinging member mounted to turn about the axis of the ratchet wheel, a pawl on said swinging member, means on the base frame engaging said swinging member to shift the pawl, a member mounted to turn about the axis of turning of the ratchet wheel and cooperating with said pawl to hold the latter out of engagement with the ratchet wheel during any amount of movement of the swinging member, an adjusting wheel mounted on the first mentioned carriage and having an arm extending therefrom, and a link connecting said arm with the pawl controlling member at a point eccentric to the axis of turning of said pawl controlling member.

SOLOMON WILE.
